UNITED STATES PATENT OFFICE.

CHARLES W. GREEN, OF SCRANTON, PENNSYLVANIA.

VALVE FOR AIR-BRAKES.

SPECIFICATION forming part of Letters Patent No. 309,845, dated December 30, 1884.

Application filed July 2, 1884. (No model.)

To all whom it may concern:

Be it known that I, CHARLES W. GREEN, of Scranton, in the county of Lackawanna and State of Pennsylvania, have invented certain new and useful Improvements in Valves for Air-Brakes; and I do hereby declare the following to be a full, clear, and exact description of the same, reference being had to the accompanying drawings, forming a part of this specification, and to the figures and letters of reference marked thereon.

My present invention relates more especially to that class of pneumatic-brake-operating mechanism wherein the air or other elastic fluid being supplied under pressure causes the release of the brakes and the charging of the reservoir, and by a diminution of pressure in the supply-pipe a connection is automatically effected between the reservoir and the mechanism controlling the brakes, whereby the latter are caused to be actuated by the compressed air contained within the reservoir; and it consists in certain improvements in the construction and arrangement of the actuating-valve and its connections, as hereinafter more fully described, and pointed out in the claims.

In the accompanying drawings, Figure 1 is a side elevation, Fig. 2 a top view, and Fig. 3 a transverse section, of a valve mechanism illustrating my present invention. Fig. 4 is a side view, partly in section, of the valve. Fig. 5 is a side view illustrating a modified arrangement of the connecting-tubes.

Similar letters of reference in the several figures indicate the same parts.

The letter A designates one head or side of the cylinder or reservoir within which the air is maintained under pressure, and from whence it is delivered to a brake-actuating mechanism of any well-known form or construction adapted for the purpose.

To the head A, and preferably projecting within the cylinder, where it will be protected from injury or interference, is screwed or otherwise detachably secured the valve chamber or casing B, provided with a removable cap, B', into which latter is secured the end of the supply-pipe A'. The valve chamber or casing B is preferably constructed of cast-iron, and provided with a tubular brass lining, B', within which works the valve C. Three

sets of passages or ports are cast, drilled, or otherwise formed through the side walls of the casing or chamber B. The passages a a 55 and b b open into the interior of the reservoir, and the passages c c' communicate, the former with the brake-operating mechanism through the pipe c', and the latter, c', with the atmosphere through the eduction-pipe c'. 60

To the inner end or head of the casing B is secured the end of a pipe, c', which communicates with the brake mechanism. The pipes c' and c' are by suitable joints and couplings connected to the pipe c', through which latter the air is conducted to and from the brake-actuating mechanism.

Within the casing B is arranged the double and reversible valve C. This valve, preferably composed of brass, is composed of the two 70 heads or pistons, C', united by a reduced portion or stem, C'. The heads C' are exactly alike, each being provided with a peripheral groove, d, for the reception of a split metallic or other suitable packing-ring, d', and with 75 a countersink or cavity, d'', within which is located a stud or pin, d'', for sustaining the spring d'. The valve as thus constructed, when placed within its casing B, ready for action, is maintained in its forward position by 80 the spring d', as shown in Fig. 3. When so held, the forward piston C' laps over and closes the ports a a, and the rear piston closes the ports c c', thus leaving only the ports b b uncovered, and opening the passage from the 85 reservoir or cylinder to the brake mechanism.

The several parts being thus arranged and disposed, the first operation is to charge the several cylinders or reservoirs. This is accomplished in the following manner: The air 90 under pressure, being turned on, is delivered through the supply-pipe A' in front of the valve C, forcing the latter back, closing the ports b b and opening the ports a a and c c'. The air is thus caused to pass through the 95 ports a a into the reservoir, and, the ports b b being closed, it cannot escape, hence is compressed and retained within the reservoir, the pressure in the supply-pipe being maintained so long as the brakes remain off or inactive. 100 If, now, it becomes necessary or advisable to actuate the brake mechanism, the pressure in the supply-pipe is diminished or the supply of air cut off. As soon as this is accomplished

the valve, aided by its spring, will be moved forward, thus again closing the ports *a a* and *c c'* and opening the ports *b b*. As soon as the ports *b b* are opened the compressed air 5 passes into the rear end of the valve-casing, and thence through the pipe *c'* to the operating-cylinder, thus causing the brakes to be applied and held in position by the air-pressure within the reservoir.

10 When it is desired to "take off" or release the brakes, it is only necessary to re-establish the pressure in the supply-pipe, when the valve will again be forced back, thereby closing the ports *b b*, thus cutting off the supply 15 of air from the reservoir to the cylinder, opening the ports *a a* to again charge the reservoir, and uncovering the ports *c c'* to open the exhaust and permit the air to escape from the cylinder into the casing between the pistons 20 *C* and out through the pipe *c'*.

The valve mechanism above described constitutes a simple, desirable, and efficient mechanism for automatically effecting the necessary operations of the brake mechanism. The casing 25 and its contained valve, being made separate from and applied to the reservoir in the manner described, can at any time be removed from one cylinder and be applied to another, or can be taken off, repaired, and returned to 30 its place. The valve—the only moving portion—is automatic in its action, and can at any time be removed and replaced by simply unscrewing the cap-plate. Moreover, as both 35 ends of the valve are the same in structure, no skill or special instructions are required for applying it within the casing, as it operates the same in either position; hence all danger from a misplaced valve is entirely avoided.

Among the important advantages gained by 40 the location of the valve and its casing within the reservoir may be mentioned the freedom which is secured against the accidental putting on of the brakes by air escaping through a loose or defective joint or coupling. As the 45 education-passages *c c'* are always open when the induction-passages *b b* are closed, any air which might escape into the pipe leading to the brake-operating mechanism will find a free passage to the atmosphere through the pipe 50 *c'*, and when the induction-passages *b b* are open and the education-passages *c c'* closed no defect in the joints or connections within the reservoir could prevent the brake mechanism

from being positively actuated and applied. Should the valves, the packing-rings, or the 55 lining of the valve-casing become worn or otherwise damaged, every facility is afforded for their removal and repair or the substitution of new parts without necessitating the removal of either the casing or reservoir and 60 while both the latter devices remain in place attached to the car.

Having thus described my invention, I claim as new—

1. In combination with the head or side of 65 the air-reservoir, the detachable valve-casing and its connecting-pipes, said casing containing the automatic valve mechanism and the removable cap-plate, substantially as described.

2. The valve-casing provided with the ports 70 *a a*, *b b*, and *c c'*, arranged and located, as described, within the reservoir, in combination with the reversible valve provided with the reduced stem and duplicate piston-heads, sub- 75 stantially as described.

3. In a brake mechanism such as described, and in combination with the reservoir thereof, the valve-casing, valve, and connecting-pipes, located wholly within and attached to the said 80 reservoir, substantially as described.

4. In combination with the air-reservoir and the valve casing or chamber located within and secured thereto, as described, the removable lining and reversible valve, and the removable cap-plate applied to the end of the valve-casing outside of the air-reservoir, sub- 85 stantially as described.

5. The combination, in a brake mechanism such as described, and with the air-reservoir 90 thereof, of the automatic valve mechanism consisting of a casing or chamber removably attached to the head and projecting within the reservoir, the valve and removable cap-plate, and the connecting-pipes, also located within 95 the reservoir, substantially as and for the purpose set forth.

6. The combination, with the air-reservoir, of the valve-casing *B*, threaded into the head of said reservoir, the cap *B'*, valve *C*, ports *a* 100 *a*, *b b*, and *c c'*, connections *c²*, *c³*, *c⁴*, *c⁵*, and *A'*, substantially as described.

C. W. GREEN.
